CLAIM

The ornamental design for a facial exerciser, substantially as shown and described.

DESCRIPTION

FIG. 1 is a perspective view of a facial exerciser showing my new design;

FIG. 2 is a side elevational view thereof, the side opposite being a mirror image;

FIG. 3 is an end elevational view thereof, the end opposite being a mirror image;

FIG. 4 is a top plan view thereof; and,

FIG. 5 is a bottom plan view thereof.

FIG. 1

FIG. 4

FIG. 2

FIG. 5
